UNITED STATES PATENT OFFICE.

ROBERT KELLEY, OF BOWIE, TEXAS.

DRIVE-BELT.

1,266,275.

Specification of Letters Patent. Patented May 14, 1918.

Application filed October 6, 1917. Serial No. 195,087.

To all whom it may concern:

Be it known that I, ROBERT KELLEY, a citizen of the United States, residing at Bowie, in the county of Montague and State of Texas, have invented certain new and useful Improvements in Drive-Belts, of which the following is a specification, reference being had to the accompanying drawings.

This invention relates to an improved drive belt, and has for its primary object to provide a drive belt for motor fans and similar light machine elements which will be very strong and durable and is so constructed that possible breakage of the belt is reduced to a minimum.

It is also an important object of the invention to provide a drive belt consisting of a single, continuous piece of leather or other flexible material which is provided with means whereby the end portions of the belt can be connected to the body portion thereof without the use of metallic fasteners and which will provide an endless drive belt of double thickness.

It is also a further general object of the invention to provide an inexpensive driving belt for light machinery which will not be liable to slip upon the belt wheels or become loosened and displaced therefrom.

With the above and other objects in view, my invention consists in the novel features of construction, combination, and arrangement of parts to be hereinafter more fully described, claimed, and illustrated in the accompanying drawing, in which,

Figure 1 is a perspective view of a driving belt constructed in accordance with the preferred embodiment of the invention;

Fig. 2 is a fragmentary plan view of the leather strap from which the belt is formed; and

Fig. 3 is a horizontal section taken on the line 3—3 of Fig. 1.

Referring in detail to the drawing, 5 designates the strip or band of leather or other suitable flexible material which is of the requisite length and thickness. This leather strap is reduced in width, as shown at 6, said reduced portions of the strap extending from points equidistantly spaced from the center of the strap to its opposite extremities. The body or wider portion of the strap is provided at spaced points with slits 7 extending across the width thereof and terminating in spaced relation to the opposite longitudinal edges of the strap.

As seen in Fig. 1 of the drawing, the body portion of the strap is bent into circular form and the relatively narrow end portions 6 lapped upon each other. These narrow end portions of the strap which extend in opposite directions, are threaded or laced through the slits 7 extending between said slits alternately upon the inner and outer faces of the body portion of the strap. 60 Each of the narrow portions 6 of the belt strap is provided in spaced relation to its free extremity with the transverse slit or opening 8, such extremities of the strap being tapered or reduced in width as indicated 65 at 9. The portions 6 of the strap are each of sufficient length to extend halfway around the body portion of the strap, and one of the tapering terminals 9 of the strap is inserted through the slit 8 in the other end 70 of the strap from the outer side of the belt and extended inwardly through one of the slits 7, while the other tapered extremity 9 of the strap is inserted through the other of the slits 8 from the inner side of the belt 75 and extended outwardly through one of the slits 7, as clearly shown in Fig. 3 of the drawings.

A driving belt constructed in the manner above explained provides two thicknesses of 80 material which are held in close, intimate contact throughout the extent of the belt. Thus, I produce a belt of great durability and without stitching, cementing, or otherwise mechanically connecting the parts of 85 the belt to each other. Such connections quickly wear out so that the belt breaks or comes apart. By lacing the narrow belt ends through the slits in the belt body, the belt is provided with spaced portions on its inner 90 face simulating teeth which have a frictional gripping engagement with the peripheral faces of the belt wheels, and counteract any tendency of the belt to slip upon the wheels. 95 Also, by lacing the belt ends to the belt body in the manner explained, the greater the pull or strain upon the belt, the tighter will the interlaced parts thereof be held together.

From the foregoing, the construction and several advantages of my improved driving belt will be clearly and fully understood. The invention is primarily designed for use in driving the ventilating fan of a motor vehicle, but it is manifest, of course, that the belt may be made of any desired width 100 and length and can be employed for use in connection with various other light machin- 105

ery. My improved driving belt is likewise susceptible of other modifications which will readily suggest themselves to one skilled in the art, and it is, therefore, to be understood that I reserve the privilege of adopting all such changes as may be fairly considered within the spirit and scope of the invention as claimed.

Having thus fully described my invention, what I desire to claim and secure by Letters Patent is:

1. A driving belt consisting of a single length of flexible material having a relatively wide body portion adapted to be arranged in circular form, and narrow end portions, said body portion of the belt being provided with spaced slits through which the narrow end portions are adapted to be laced so that end portions of the belt will extend alternately upon the inner and outer faces of the belt body.

2. A driving belt consisting of a single length of flexible material having a relatively wide, intermediate portion provided with spaced slits therein, and narrow end

portions each of substantially one half the length of the intermediate portion of the belt, said wider body portion being adapted for arrangement in circular form and the narrow end portions extending in relatively opposite directions and laced through the slits in said intermediate portion of the belt, the terminals of said narrow end portions of the belt lapping upon each other and being inserted through adjacent slits.

3. A driving belt consisting of a single length of flexible material having equi-distantly spaced transverse slits in the medial portion thereof, said medial portion of the material being adapted for arrangement in circular form and the end portions of the material for insertion through said slits to lie in close contact with said medial portion.

In testimony whereof I hereunto affix my signature in the presence of two witnesses.

ROBERT KELLEY.

Witnesses:

L. C. McMURRAY,
JOHN SPEER.
